PLYWOOD LIFEBOAT

Ludwig S. Baier, Portland, Oreg.

Application June 1, 1942, Serial No. 445,327

6 Claims. (Cl. 9-3)

My invention, which relates to the art of boat building, has particular reference to life boats.

Primarily, the invention has for its object to provide a light-weight, strong and relatively inexpensive-to-build life boat to carry a maximum number of persons.

Again, it is an object to provide a life boat employing a minimum amount of metal in its hull construction.

A further object is to provide a life boat the shell of which is composed of layers of plywood so constructed that ordinary calking is not required.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1^a and Fig. 1^b, when joined on the lines A—B, comprise a top plan view of one-half of a life boat of my present invention.

Figs. 2^a and 2^b, when joined on the lines C—D, comprise a longitudinal section at approximately mid-ship of a life boat of my invention.

Fig. 3 is a transverse section, taken at about mid-ship.

Fig. 4 is an enlarged detail section on the line 4—4 of Fig. 5.

Fig. 5 is a section on approximately the line 5—5 of Fig. 3.

Fig. 6 is a top plan and part horizontal section of the forward half of a life boat, showing a modification of my invention.

Fig. 7 is a central vertical section of the same.

Fig. 8 is an enlarged detail cross section on the line 8—8 of Fig. 6.

Fig. 9 is a detail view of one of the disengaging mechanisms used in the first embodiment of the invention.

Fig. 10 is an enlarged detail section showing how the grab rods are secured.

In the drawings, in which like numerals and letters of reference indicate like parts in all the figures, 1 is the stem iron which comprises a body having flanges 2 and which extends from the sheer to the keel. The stem iron has its flanges widened adjacent its upper end as at 3 for a purpose presently understood.

A pair of spaced metal plates 4 are welded, as at w, to the stem iron 1. A pin 46 passes through these plates 4 and through the shell and though

the widened portions 3 of the stem iron, the pin being riveted over at its ends. Spacer pipes 45 are located on the pin between the plates 4 and the portions 3. The spacers 45 also serve as braces for the plates 4.

Pivoted on the pin 46 is the hook 53 that holds the boat-lowering tackle link 57 while lowering the boat from the deck of a ship, of which more will be said later.

The stern post 5, like the stem iron 1, is made of metal with flanges 6 and widened portions 7. Spaced plates 8 are also welded at w to the stern post 5, there being a pin 46 and spacers 45 employed as at the stem of the boat. Pivoted on the pin 46 of the stern disengaging-apparatus is a hook 53 for the aft link 57 of the boat lowering tackle.

Both fore and aft, between the plates 4—4, is pivoted at 56 a weighted latch 55 which normally engages the pivoted hook 53, a stop pin 54 serving to hold the hook 53 against turning in one direction beyond a predetermined position (see Fig. 9). An eye bolt 47 passes through each pair of plates 4 and carries a spacer 52 between the plates.

A pulley 51 is mounted on each eye bolt, over which pulley the release cable 49 passes and has one of its ends connected to the weighted end of latch or lever 55.

At the stern suitable gudgeons 9 are welded to the stern post 5 for the reception of the gudgeon pins 32 of the rudder 30. The rudder 30 is made of plywood (about $\frac{3}{4}$ ") and is fitted with steel straps 31.

The keel 10 of the boat is preferably made of oak and the keelson 11 is preferably made of fir.

The shell 12 of the boat, bottom, side and bilge, is made of two layers 12^a and 12^b of water-proof fir plywood. When the strakes are made of more than one length, the butts 13, 14 (see Figs. 4 and 5) are staggered and one course forms a butt strap for the other. Butts are triple riveted with copper clout nails 15, clinched and staggered. A water-proof cement is applied to all faying surfaces in addition to the nails and screw fastenings.

Inside seam battens 16 extend the full length of the boat. Outside filler battens 17 also extend the full length of the boat and are of wedge or tapered form in cross section (see Fig. 5). The edges of the shell strakes 12^a, 12^b are correspondingly shaped so that when the battens 17 are secured to the battens 16 and frames 21 by bolts 19 and screws 18 a water-tight joint is obtained.

The frames comprise bottom elements 20, side

elements 21 and, where necessary, plywood knees 22.

A suitably spaced number of thwarts 23 extend across the boat and are supported midway their lengths, where necessary, by braces 44 that rest on the keelson 11. Side seats are constituted by slats 24 secured to the thwarts 23 (Fig. 3). The thwarts 23 are secured at their ends to the side frame members 21 by angle brackets 27 and the gunwale 26 is suitably braced by braces 25 secured to it and to one of the slats 24.

The gunwale is provided with suitably located row locks 28 and it is also provided with a nosing 29.

The footings 34 are laid on the bottom frames 20 and are removably held in place by toggles 35. A hand-hole 36 is provided in the footings for access to the usual automatic plug (not shown) employed in life boats.

Air tanks 37 of galvanized steel are of elliptical cross section and are secured in place by straps 43, one end of each of which is secured to a seam batten 16 and the other end of which is secured to one of the seat slats 24 (Fig. 3).

Grab rods 38 are mounted by means of stanchions 37 secured to filler battens 17 (Fig. 3).

Painter rings 40 in staples 41 are provided fore and aft, the staples having their pads welded to the stem iron 1 and stern post or iron 5, respectively.

Life lines, indicated by dot and dash lines 42 in Figs. 1^A—1^B, with seine floats are secured to the boat.

Disengaging cables, indicated by dotted lines 49 in Figs. 2^A—2^B, pass through guides 48; at the aft end of the boat the fore and aft cables 49 are connected to a pull member 50. By pulling on member 50 the tiller man can release the fore and aft hooks 53 to free the boat from the launching tackle. It will be seen by reference to Figs. 2^A and 2^B that the releasing gear is rigidly mounted directly on the stem and stern irons. Thus the weight of the boat as it hangs from the suspending tackle, including the load, is carried by the stem and stern irons, which stem and stern irons actually serve as two hooks that cradle the load, extending to the ends of the keel. The tiller is indicated at 33 in Fig. 2^A.

58 designates foot rests for the oarsmen, 59 a mast strap, and 60 a socket into which a mast (not shown) is stepped.

61 designates a steel liner and 62 a steel keel-guard at the bow end of the boat. At the stern end of the boat a stern plate 63 is welded to the stern post 5 and set into the keel 10 to which it is riveted and bolted at 19.

In the modification of the invention shown in Figs. 6 and 7, parts similar to those in Figs. 1 and 2 bear the same reference letters plus the index letter x.

Instead of employing metal tanks, water-tight compartments can be formed with frames 64, bulkheads 65, walls 66 and tops 67.

These compartments may be left as air chambers or may be filled with kapok.

Having now given a general description of my new and improved life boat embodying my invention, the following is a brief general résumé of the construction materials, etc., used in building a twenty-two foot boat:

Stem and stern.—The stem, sternpost and forefoot shall be constructed of $\frac{1}{8}$ " steel plate formed in one piece to extend from the sheer to the keel, drilled on 2" centers, staggered and countersunk for $\frac{1}{8}$ " bolts and rivets. The steel shall

be fitted to the outside of the shell and shall be shaped, as shown, to take disengaging gear pin. Gudgeons of steel shall be welded to the stern post and skeg. In a motor-propelled boat a steel stern tube shall be welded water-tight to the skeg, babbitted at the aft end and provided with a bronze stuffing box with a bronze gland and lock nut. A $\frac{1}{4}$ " steel plate skeg shall be welded to the stern post.

10 *Keel and keelson.*—The keel shall consist of a fir inner keelson shaped to suit and screw-fastened to the shell; where lapped at the ends over the forefoot it shall be through-bolted with $\frac{1}{4}$ " carriage bolts. The oak keel shall be through-bolted at each frame with a $\frac{3}{8}$ " carriage bolt and at 12" centers with $\frac{1}{4}$ " carriage bolts.

15 *Shell.*—The shell, bottom side and bilge shall consist of two layers of $\frac{1}{4}$ " water-proof fir plywood. (It is optional to use a single length on the outside strake if possible to obtain the same for boats of this length.) Butts shall be staggered and one course shall form a butt strap for the other. Butts, if used, shall be triple riveted with copper clout nails clinched and staggered and spaced on 2" centers. Additional copper clout nails shall be quilted on 12" centers over the entire hull (see 15, Figs. 2^B and 2^A). A water-proof cement shall be applied to all faying surfaces in addition to the nails and screw fastenings.

20 *Seam battens.*—A fir inside batten shall be in one full length of a total cross section area of $1\frac{1}{2}$ " x $3\frac{1}{2}$ " and be shaped as shown. An outside filler batten of the size required and shaped to form a positive lock at the seam shall be screw and bolt fastened.

25 *Frames.*—All frames shall be of sawed oak or w. p. plywood bolted at the keel and screw fastened to the shell and bracketed at the bilge with $\frac{3}{4}$ " plywood. Side frames shall be clipped to the under side of the side seat and be as shown. Bottom frames shall be in one piece except at the ends where they shall be secured to a floor piece of $\frac{3}{4}$ " plywood at the keel.

30 *Thwarts and gunwale seat.*—Thwarts shall be of "B" or better fir, and shall be screw and bolt fastened throughout. Gunwale braces of steel shall be bolted to the gunwale and seat to conform to existing rules. Side seats shall be as shown, the out-board strake of fir being sawed to shape and the remaining pieces of $1\frac{1}{4}$ " x $1\frac{3}{4}$ " fir batten sprung in place and bolted.

35 *Nosing and gunwale.*—The gunwale and nosing shall be of oak, and fastened in accordance with existing rules. Gunwale and nosing may be made up in two lengths. Rowlocks shall be located as required for oars and emergency steering tiller bar.

40 *Rudder.*—A rudder of $\frac{3}{4}$ " plywood shall be fitted with steel straps and gudgeon pins to conform to regulations and be of the size and shape indicated, and shall be fitted with an oak steering tiller arm. A metal edging of 16 gauge galvanized steel shall be nailed to the rudder, as shown.

45 *Footings.*—Footings may either be as shown or in narrow strakes to suit the requirements of the Department of Commerce. Metal toggles shall be secured to frames as required. A hand-hole for access to the automatic plug shall be provided in the footings as shown.

50 *Air tanks.*—The air tanks shall be of 22 gauge galvanized steel soldered air-tight and of the size and shape indicated. They shall be supported by galvanized steel straps and made port-

able. There shall be sufficient air tank capacity provided for a rowing or motor-driven boat along the sides without end tanks.

Painting and galvanizing.—All surfaces of the plywood, both inside and out, shall be primed after assembly with one coat REZ plywood primer, or equal resin primer and then painted two coats of lead and oil paint. All metal and fastenings shall be galvanized after fabrication.

Disengaging apparatus.—A quick-acting double end release gear, as shown, shall be fitted in the boat and face plates welded to the stem and stern irons and be galvanized after fabrication.

Grab rods.—Grab rods of 1" diameter, of oak, ash or equally hard wood, shall be fitted to the under side of the hull for a distance of two-thirds the length of the boat. They shall be supported by cast steel galvanized stanchions spaced approximately 20" centers, except in way of chocks, where they shall be omitted. End stanchions shall be blind at one end. A space of 1½" shall be provided between the inner side of the rod and the outer side of the hull plant.

Motor.—In boats of this size using a motor, suitable fir engine timbers, sided 2½" and molded to suit the hull, shall be through-bolted and fastened to support the motor. Gas tank or tanks of galvanized steel shall be in accordance with existing regulations and secured to permit removal for inspection.

Painter and life line.—A painter ring shall be secured to the bow and stern by means of welding a staple pad eye to the stem and stern posts. A life line in bights not to exceed 3' 0", with a seine float secured to each bight, shall be provided and installed. Painter and life line shall be of sizes and capacities as required by existing regulations of the Department of Commerce.

From the foregoing description, taken in connection with the accompanying drawings, it is thought the construction and advantages of the invention will be clear to those skilled in the art.

What I claim is:

1. In a plywood-shell life boat having seams and frames to which the shell is secured: the improvement which comprises inner battens extending longitudinally of the shell and overlying the seams between the strakes, the inner battens being recessed into the frames, outer filler battens extending longitudinally of the shell and lying in the seams between the strakes, and bolts with nuts passed through the frames, the inner battens and the outer filler battens to secure the battens together and to the frames and locking the shell strakes in place at the seams.
2. A plywood-shell life boat constructed according to claim 1 and provided with screws passed through the shell strakes into the inner battens at intervals along the battens.
3. A plywood-shell life boat constructed according to claim 1 and provided with screws passed through the outer battens into the inner battens.
4. A plywood-shell life boat constructed according to claim 1 and provided with screws passed through the shell strakes into the inner battens at intervals along the battens and provided further with screws passed through the outer battens into the inner battens.
5. A plywood-shell life boat constructed according to claim 1 in which the longitudinal strakes are beveled and the filler battens are correspondingly bevelled.
6. In a plywood life boat wherein is provided frames and a shell; the improvement wherein the longitudinal edges of the strakes are bevelled, longitudinally disposed into battens against which the strakes lie with their bevelled edges separated, filler battens shaped to fit the bevelled edges of the strakes and lock the same to the inner battens, and means securing the inner and outer battens together and to the frames.

LUDWIG S. BAIER.
